CLAIM

The ornamental design for a display panel of an electronic navigation device with a graphical user interface, as shown and described.

DESCRIPTION

The file of this patent contains at least one drawing or photograph executed in color. Copies of this patent with color drawings/photographs will be provided by the Office upon request and payment of the necessary fee.

FIG. 1 presents a front view of a display panel of an electronic navigation device with a graphical user interface; FIG. 2 is a second embodiment thereof;

FIG. 3 is a third embodiment thereof; and,

FIG. 4 is a fourth embodiment thereof.

The outermost broken lines showing an electronic navigation device illustrate environmental subject matter, whereas the broken lines showing a display panel and elements of the graphical user interface illustrate portion of the article. No subject matter depicted in broken lines forms part of the claimed design.
